4 Claims. (Cl. 75—126)

ABSTRACT OF THE DISCLOSURE

A high speed tool steel which in its hardening state has improved hardness suitably of the order of R_c 70 hardness and thus improved wear resistance as well as improved toughness which steel consists of, on a percentage basis, 1.15 to 1.25 carbon, 4.00 to 4.5 chromium, 4.25 to 5.00 tungsten, 1.85 to 2.15 vanadium, 6.75 to 7.75 cobalt, 7.00 to 8.00 molybdenum, .20 to .40 manganese and .15 to .45 silicon, the balance being iron and residual impurities.

This invention relates to a new and improved steel composition and more particularly to a steel composition especially adapted for tool steels employed in high speed operations.

Among the properties which are desired for high speed tool steels are versatility, low ingot cost, suitable grindability, workability and response to heat treatment, and adequate tool life as related to heavy cutting and high speed machining and measured in terms of red hardness and abrasion resistance. Tungsten, molybdenum, vanadium, chromium and cobalt are the alloying elements found in these steels.

It is an object of this invention to provide a tool steel having high speed machining features superior to present steel compositions while still maintaining properties of versatility, suitable grindability, and workability and adequate response to heat treatment.

Other objects of the invention will become apparent from the description to follow:

The objects of this invention are attained in a tool steel having the following percentage composition:

C	1.15—1.25
Cr	4.00—4.50
W	4.25—5.00
V	1.85—2.15
Co	6.75—7.75
Mo	7.00—8.00
Mn	.20—.40
Si	.15—.45

The balance iron plus residual impurities.

Some preferred percentage compositions were analysed as follows:

	C	Mn	Si	P	S	Cr	W	V	Mo	Co
(1)	1.20	.30	.40	.014	.010	4.33	4.49	2.02	7.62	7.34
(2)	1.20	.25	.40	.013	.011	4.34	4.57	2.07	7.60	7.20
(3)	1.22	.29	.42	.014	.010	4.32	4.52	2.02	7.64	7.34

The balance iron plus residual impurities.

2

Phosphorus and sulfur are considered as impurities at their low levels, the manganese being employed to reduce the harmful effects of sulfur on the hot workability of the steel.

5 A preferred heat treatment of the steel includes a pre-heat step of 1500—1550° F. followed by hardening at 2175—2225° F. with a recommended temperature being 2200° F. The material is then tempered at from 950—1200° F. with maximum hardness produced by a triple temper at 975—1025° F. with 2 hours of each temper.

An induction heat (H245) having the composition in preferred analysis No. 1 was melted, cast and processed to tool bit size for a comparative evaluation with the tool steel (H248) described in U.S. Patent 2,996,376.

15 This latter composition analysed as follows:

C	1.12
Mn	0.31
Cr	4.32
W	6.58
V	1.99
Mo	3.83
Co	4.70

Some of the test data are graphically illustrated in FIG-25 URES 1-3.

TOUGHNESS COMPARISONS

Un-notched izods were prepared by fully heat treating oversize bars, then carefully finish grinding in the hardened condition using a soft wheel and low metal removal rate. All specimens were magnafluxed prior to testing.

The results are shown below and it will be noted that H245 is marginally superior to H248.

Heat No.	Hardness	Un-notched Izod Impact Strength Values	Average Izod
H245	69.5	6-6-22.5-5-5-9-6-13-22-----	10.5
H248	68.5	11-8-8-11-10-9-----	9.5

TOOL LIFE TESTS

Four sets of tool steels were cut from $\frac{3}{8}$ " square annealed stock. Two sets which were used corresponded to the analysis of H245 and H248. The other two tool steels analysed as follows:

	C	Mn	Si	Cr	W	V	Mo	Co
A.1.S.1. T-15	1.25	.30	.39	4.25	10.00	4.30	2.50	5.50
A.1.S.1. M-34	.90	.30	.25	3.75	1.45	2.05	8.70	8.25

50 The tools ground from these grades had the following dimensions:

Back rake	degrees	0
Side rake	do	10
Side cutting edge angle	do	15
End cutting edge angle	do	5
Relief	do	5
Nose radius	inches	.030

A.1.S.1. H-11 was the material used to rate the tools. 60 A 3" diameter rod, 15" long of H-11 was quenched and tempered at 50 R_c . Tool life was then measured against cutting speeds and the results are shown in FIG. 3. It will be observed that composition H245 has about twice the wear life of H248.

HARDNESS COMPARISONS

(1) Room temperature hardness.—Samples about $\frac{1}{2}'' \times \frac{1}{2}'' \times 1''$ were cut from the $4\frac{1}{4}''$ R_c sq. billets. Samples were salt hardened from 2100, 2150, 2200, 2250, 2300 and 2350° F., interrupt quenched at 1050° F. subsequently double tempered (2 hours each) at 1000, 1100 and 1200° F. The resultant hardness shown in FIGURES 1 and 2 indicate that the optimum hardening temperature is in the range 2200 – 2250° F. Hardness of 68–69 R_c was obtained on both compositions after hardening and then tempering at 1000° F. Applicants' analysis (H245) offers the most resistance to tempering, when hardened from 2250° F., which indicates superior hardness.

(2) Hot hardness.—A second hardness evaluation was determined by heat treating four samples: H245, H248, T-15 and M-34 and subjecting them to hot hardness tests. The heat treatment for H245, H248 and M-34 were as follows:

	$^{\circ}$ F.
Preheat	1500–1550
Salt harden	2190–2210
Salt interrupt	1050
Double draw 2 hrs. + 2 hrs. at 1025° F.	

T-15 was given a heat treatment at somewhat higher temperatures as follows:

	$^{\circ}$ F.
Preheat	1550–1600
Salt harden	2225–2250
Salt interrupt	1050
Double draw 2 hrs. + 2 hrs. at 1025° F.	

The results of the heat treatment tests were as follows:

HOT HARDNESS				
Temperature at Test, $^{\circ}$ F.	H245	H248	M34	T15
RT	70.0	68.0	66.0	68.0
600	62.7	62.5	60.5	61.8
800	61.9	62.5	60.3	60.9
900	61.0	59.5	59.3	58.3
950	60.2	59.0	57.9	57.6
1,000	59.5	58.0	57.4	56.7
1,050	58.8	57.2	56.1	55.7

Grindability.—Samples of H245 and H248 were tested under the following conditions:

Machine	Gallmeyer & Livingston Surface Grinder.
Wheel specification	PA46–G8–V40.
Wheel size	$7'' \times \frac{1}{2}'' \times 1\frac{1}{4}''$.
Wheel speed	3500 r.p.m.
Material ground	Various kinds as shown below ($2'' \times \frac{5}{8}''$ area).
Grinding fluid	None—dry grinding.
Table speed	50 f.p.m.
Crossfeed	.060" per table reverse.
Infeed per pass	.003".
Number of passes	150.
Dressing technique	Open—.001" per pass until wheel trued up.

The following results were obtained:

Material Number	Ground Rock-well	Metal Removed Inches	Metal Removed Grams	Wheel Loss, Grams	Ratio of weight of metal removed/weight of wheel removed	Finish M.I., RMS	Burn	Load on Wheel	Check on Steel
H245	C 67	.437	74.54	5.90	12.6	85	Lt. Brown	Some	No.
H248	C 68	.428	71.14	8.30	8.6	80	Tan	Light	No.

It will be observed that on the basis of the above-noted tests, H245 is superior in hot hardness and grindability, and markedly better in tool life than H248, while still maintaining equivalent toughness to H248.

We claim:

1. A high speed tool steel having the following percentage composition:

10	C	1.15–1.25
10	Cr	4.00–4.50
10	W	4.25–5.00
10	V	1.85–2.15
10	Co	6.75–7.75
15	Mo	7.00–8.00
15	Mn	.20–.40
15	Si	.15–.45

The balance iron plus residual impurities.

2. A high speed tool steel having the following percentage composition:

20	C	1.20
20	Mn	.30
20	Si	.40
25	P	.014
25	S	.010
30	Cr	4.33
30	W	4.49
30	V	2.02
30	Mo	7.62
30	Co	7.34

The balance iron plus residual impurities, the latter including sulfur and phosphorus.

3. A high speed tool steel having the following percentage composition:

40	C	1.20
40	Mn	.25
40	Si	.40
40	P	.013
40	S	.011
45	Cr	4.34
45	W	4.57
45	V	2.07
45	Mo	7.60
45	Co	7.20

50 The balance iron plus residual impurities, the latter including sulfur and phosphorus.

4. A high speed tool steel having the following percentage composition:

55	C	1.22
55	Mn	.29
55	Si	.42
55	P	.014
55	S	.010
60	Cr	4.32
60	W	4.52
60	V	2.02
60	Mo	7.64
60	Co	7.34

The balance iron plus residual impurities, the latter including sulfur and phosphorus.
